UNITED STATES PATENT OFFICE.

FRANK S. NOVOTNY, OF ST. PAUL, MINNESOTA, ASSIGNOR OF ONE-HALF TO JOHN F. FITZPATRICK, OF ST. PAUL, MINNESOTA.

SINGLE-TRIGGER MECHANISM FOR DOUBLE-BARREL GUNS.

1,268,760.

Specification of Letters Patent.

Patented June 4, 1918.

Application filed August 21, 1916. Serial No. 115,982.

To all whom it may concern:

Be it known that I, FRANK S. NOVOTNY, a citizen of the United States, residing at St. Paul, in the county of Ramsey and State of Minnesota, have invented certain new and useful Improvements in Single-Trigger Mechanism for Double-Barrel Guns, of which the following is a specification.

My invention relates to improvements in guns, particularly to the trigger mechanism of double barrel shot guns, its object being to provide improved means through the medium of which the hammers of both barrels will be actuated by a single trigger. The object of my construction is to provide mechanism which can be easily and cheaply applied to the well known types of guns, and to provide mechanism that is particularly positive in its action and proof against accidental or simultaneous actuation of the hammers.

In the accompanying drawings forming part of the specification,

Figure 1 is a perspective view of the lock mechanism of a shot gun of the well known Parker type, embodying my features of invention.

Fig. 2 is a side elevation of the same, showing the parts cocked.

Fig. 3 is a similar view to Fig. 2 but looking toward the opposite side and showing the position of the parts after actuation of the right hand hammer.

Fig. 4 is a detail of a supporting bracket for the sear actuating parts.

Figs. 5 and 6 are details of the sear actuating slide.

Fig. 7 is a view of the left hand sear and coöperating parts shown in position during the beginning of the firing action of the right hand hammer, and

Fig. 8 is a similar view to Fig. 7 showing the parts in position during the firing of the right hand hammer and immediately after the parts have passed the position shown in Fig. 7.

In the drawings A represents a gun frame provided with a rearwardly extending tang 2 between which and the trigger plate 3 the stock (not shown) is secured. Pivotal support in the ordinary manner in the gun frame A are the usual hammers formed with points 4 which strike the shells in the ordinary manner. Arranged in connection with the ham-

mers are sears 5 and 5^a, said sears having pivotal support in the frame and operating in the ordinary manner. The coöperative relationship of the sears and hammers being that of the well known Parker type of gun, and forming no novel part of the present invention are not shown in detail.

Pivotal support in the trigger plate is a single trigger 7, and for the purpose of actuating the sears from said single trigger I provide the following parts:

Having pivotal support 8 upon the trigger plate is a bracket 9, a sear actuating bar 10 being slidably supported by said bracket. Said bracket is normally held pressed down against the trigger plate by a spring 11. The slide 10 fits within the horizontal groove 11^a of the bracket, the front end 12 slidably extending through the supporting block 13 forming part of the trigger plate, and the opposite end of the slide extending through the downwardly extending rear end 14 of the bracket, a spring 15 being interposed between the slide and the end 14 of the bracket to hold the slide in a forward position.

The slide is forced to the rear position shown in Fig. 1 against the tension of the spring 15 by means of an arm 16 having hinge support 17 upon the rear face of the breech block. The usual locker lever 18 is provided, said lever being actuated in the ordinary manner to allow breaking of the gun. The bolt 19 is forced rearwardly to actuate the arm 16 and shove the slide to the position shown in Fig. 1. The slide is held in this position by the following described parts:

Secured pivotally at the right hand side of the bracket 9 and adjacent to the rear end thereof is an outwardly and forwardly extending spring 20, said spring being formed at its free end with a beveled hook nose 21. The slide is formed with a laterally projecting lug 22, which, when the slide is pushed back by the arm 16 will depress the free end of the spring in passing over the nose 21, the free end of the spring thereafter springing back to bring the nose in front of the block and form a lock holding the slide in the withdrawn position shown in Figs. 1 and 3. In this position the lug 22 stands beneath the free end of the right hand sear 5.

With the parts in the position shown in Fig. 2 the raising of the trigger will, through

its contact with the under side of the slide, raise the slide and by means of the contact of the lug 22 with the under side of the sear 5 raise the free end of the sear to release the right hand hammer. In the operation thus described the raising of the slide lifts the lug 22 out of locking engagement with the spring nose 21, permitting the slide to be restored to the position shown in Fig. 2 under the impulse of the spring 15.

The left hand sear is formed at its free end with a laterally extending bevel offset 23 and with an upwardly extending vertical lug 24 a short distance in front of, and spaced from, said offset 23. The slide is formed upon its left side with an outwardly extending lug 25 for actuating the left hand sear. When the parts are locked in the position shown in Figs. 1 and 3 the lug 25 will, as shown in Fig. 1, stand beyond the free end of the left hand sear so that the pulling of the trigger to actuate the right hand sear, as already described, will raise the lug 25 above the free end of the left hand sear, the forward movement of the slide causing the lug 25 to slide over the beveled free edge 23 of the left hand sear and thereafter drop down between the free edge 23 of the sear and the lug 24 and pass under the lug 24 as the slide is restored to the position shown in Fig. 2.

Thus, in the position of the parts shown in Fig. 2 the lug 25 stands underneath the sear lug 24 so as to raise the left hand sear to release the left hand hammer in the lifting movement of the trigger. In this position of the parts the lug 22 which projects outwardly from the right side of the slide will extend behind the offset of the free end of the right hand sear so that any lifting movement of the slide by the trigger will not cause the said lug 22 to engage with the right hand sear. Therefore with the parts in the position shown in Fig. 2 the actuation of the trigger can only lift the left hand sear to actuate the left hand hammer.

For the purpose of locking the parts in position where only the left hand hammer can be actuated I provide a slide 26 which carries an upwardly and rearwardly extending arm 27 the free end of which normally stands in front of the free end of the spring 20. By sliding the part 26 rearwardly the free end of the arm 27 will pass over the free end of the spring 20 depressing said spring and holding the free end of said spring depressed under the arm 27. With the free end of the spring depressed the showing back of the slide will carry the lug 60 freely over the free end of the spring and thus prevent the lug 22 being engaged with the spring to hold the slide retracted. Therefore with the spring depressed there is no means of locking this slide in the retracted position necessary to bring the lug

22 in position to actuate the right hand sear.

In the position of the parts shown in Fig. 7 the trigger has just been actuated to operate the right hand sear as heretofore described. This operation of the right hand sear first causes the lug 25 to pass over the beveled offset 23 of the left hand sear holding said sear down and thereby preventing the left hand sear being jarred into 75 actuating position while the right hand sear is being actuated. The continued movement of the parts in the operation of the right hand sear brings the lug 25 against the vertical lug 24 exerting pressure against said lug to continue to hold the left hand sear from jarring, the lug 25 passing underneath the vertical lug 24 as shown in Fig. 2 upon the release of the trigger. In the position shown in Fig. 2 the actuation of the right hand sear to operate the right hand hammer has been completed and the parts have assumed a position for the operation of the left hand sear as heretofore described.

I claim:

1. In trigger mechanism for double barrel guns, a pair of sears, an interposed actuator slide having oppositely extending lugs underlying the sears for raising the same, a trigger underlying the slide to lift the same, and a bracket pivoted at its forward end and formed with a seat slidably supporting the slide, said bracket also having a rearwardly extending arm formed with a downturned terminal portion for guiding the slide. 90

2. In a single trigger mechanism for double barrel guns, a pair of sears one of which has its rear end portion beveled and formed with a cut out, and a sear actuator interposed between the sears and provided with 105 oppositely extending sear-engaging lugs, one of which is inclined forwardly and upwardly for riding over the beveled end of said sear and into the cut out for engaging beneath said sear to effect subsequent operation thereof. 110

3. In a single trigger mechanism for double barrel guns, a pair of sears one of which has a beveled offset on its rear end and a vertical stop in advance of said offset, and 115 a sear actuator having oppositely extending lugs for lifting the sears, one lug inclining forwardly to ride over the offset and abut the vertical stop to hold the said sear against operation on movement of the other 120 sear.

4. In a single trigger mechanism for double barrel guns, a pivotally mounted bracket having a rearwardly extending arm whose terminal is downturned and perforated, a sear actuator slide supported by the bracket, said slide having a rearwardly extending part received by the perforated arm for guiding the slide in its movements, a coiled spring encircling the slide part be- 130

5 between the bracket arm and the body portion of the slide for urging the latter forwardly, said slide also having a forward extension, a rearwardly swinging arm normally free from the latter and adapted to engage the same for moving the slide rearwardly, and a bolt slidable on the breaking of the gun for swinging the last arm.

10 5. In a single trigger mechanism for double barrel guns, a block, a bracket pivoted at its forward end to the block, a sear actuator slidably supported by the bracket and provided with a forward extension projecting beyond the block, a rearwardly swinging arm normally free of the extension and adapted to engage the same for moving the actuator rearwardly, and a yieldable catch for engaging the slidable actuator when moved rearwardly for holding the 20 same.

15 6. In a single trigger mechanism for double barrel guns, a pair of sears, an actuator therefor, a movable catch for holding the actuator in a set position to operate the first sear, and means engageable with the catch for locking the same inoperative to prevent setting of the actuator to actuate a sear.

20 7. In a single trigger mechanism for double barrel guns, a pair of sears, an actuator therefor, a spring latch adapted to engage the actuator for holding the same in a set position to operate a sear, and a lock movable to engage over the latch and hold 25 the same depressed from the path of the actuator.

25 8. In a single trigger mechanism for double barrel guns, a pair of sears, an actuator therefor, having a projecting lug, a spring latch fixed at one end and having its other end of hook form to engage the lug and thereby hold the actuator from movement, the upper face of said hook end being beveled, and a lock slidably mounted 40 and formed with an angular arm terminating in a hook to engage the beveled face of the latch for depressing the latter from normal position and interlocking with its hook end to retain the same inoperative.

45 9. In a single trigger mechanism for double barrel guns, the combination of two hammers, a sear for each hammer, a slide positioned between said sears, means for holding the slide in retracted position, a 50 single trigger arranged in position to be actuated to release the slide from retracted position, means actuated by the slide as the

same is released to operate the left hand sear, a lug projecting outwardly from said slide in position to engage with and hold the left hand sear in normal position while the right hand sear is being actuated, said lug being thereafter engageable with the left hand sear to actuate the same through the medium of said single trigger. 60 65

10 10. In a single trigger mechanism for double barrel guns, a pair of sears, an interposed actuator having oppositely extending sear actuating lugs, means engaging one lug to hold the actuator set in a position for 70 operating one sear, and means for engaging the first means to lock the same inoperative relative to said specified sear.

15 11. In a single trigger mechanism for double barrel guns, a block, a sear on each 75 side thereof, a bracket pivoted to the block and provided with a rearward extension having a downturned terminal and an upstanding slotted spring guide in advance of the latter, a leaf spring secured on the extension rearwardly of the guide and passing through the latter into the block for yieldingly holding the bracket down, an actuator slidably carried by the bracket for actuating the sears and provided with a rearwardly extending rod slidably received by the downturned terminal of the bracket extension, and a coiled spring encircling the rod between the downturned terminal and actuator body for urging the latter forwardly. 80 85

20 12. In a single trigger mechanism for double barrel guns, the combination of two hammers, a sear for each hammer, a slide positioned between said sears, a lug extending horizontally outward from the left hand sear and a perpendicular lug extending outwardly from said left hand sear and spaced from said horizontal lug, and a lug extending outwardly from the left hand side of 90 said slide, and adapted after said trigger is actuated to actuate the right hand sear, to first pass over said horizontal lug and hold the said left hand sear down and thereafter pass to impinging position against said perpendicular lug and upon said trigger being released to pass under said perpendicular for the purpose set forth. 95 100 105

In testimony whereof I affix my signature in presence of two witnesses.

FRANK S. NOVOTNY.
